RAILWAY CAR TRUCK

George E. Dath, Mokena, Ill., assignor to W. H. Miner, Inc., Chicago, Ill., a corporation of Delaware

Application June 29, 1944, Serial No. 542,676

8 Claims. (Cl. 188—33)

This invention relates to improvements in railway car trucks.

One object of the invention is to provide in a railway car truck means for snubbing or dampening the action of the truck springs, comprising friction means attached to and actuated by a member of the brake rigging of the car to engage the bolster of the truck and frictionally oppose vertical movement thereof when the brake shoes of the brake mechanism are released from engagement with the car wheels.

A more specific object of the invention is to provide in a railway car truck comprising a body bolster and springs supporting the bolster, friction means in the form of shoes or blocks having frictional engagement with the bolster to oppose vertical movement thereof, thereby snubbing the action of the truck springs, wherein the friction shoes or blocks are carried by and fixed to the usual brake beam of the brake rigging of the car whereby when the brakes are released by movement of the brake beam in a direction toward the bolster, the shoes are brought into frictional engagement with the bolster to provide the desired snubbing action.

Other objects of the invention will more clearly appear from the description and claims herein-after following.

In the drawings forming a part of this specification, Figure 1 is a side elevational view of a portion of a railway car truck, illustrating my improvements in connection therewith. Figure 2 is a top plan view of Figure 1, showing one side portion only of the truck, said view being partly broken away. Figure 3 is a vertical sectional view, lengthwise of the car, corresponding substantially to the line 3—3 of Figure 2 and illustrating a modified form of the invention. Figure 4 is a transverse, vertical sectional view, corresponding substantially to the line 4—4 of Figure 1, said view being broken at the central portion of the railway car truck.

In said drawings, 10 indicates one of the side frame members of a railway car truck of the well-known "unit" type. The side frame 10, as shown, is in the form of a casting and has top and bottom members 11 and 12 connected by spaced, vertical sections 13—13 forming guides for the truck bolster. On the inner side of each side frame, guides 14—14 are provided to the front and rear of the opening between the spaced, vertical sections 13—13. The guides 14—14 are formed by inwardly extending, top and bottom flanges 15 and 16 and connecting end section 17 projecting from the inner side wall of the side frame at the bottom

member 12 thereof. The flanges 15 and 16 incline upwardly in directions toward the front and rear of the truck, thus presenting inclined guide channels closed at their outer ends.

As shown most clearly in Figure 4, the truck includes two side frame members 10—10 located at opposite sides of the truck. The truck includes, in addition, a truck bolster 18, as shown in Figures 1, 2, and 3, and wheels 19—19 at opposite sides of said truck. The bolster 18 has its opposite ends guided between the vertical sections 13—13 of the truck side frames 10—10 and is supported by the springs 20—20. As most clearly shown in Figure 1, the sections 13—13 are inwardly offset at their upper end portions to provide guides 21—21 which cooperate with guide seats 22—22 at the sides of the bolster 18. The truck illustrated in the drawings is of the spring plankless type and the truck springs are supported directly on the bottom members 12—12 of the side frames 10—10, the usual spring plates being employed at the top and bottom of each cluster of truck springs.

The brake beams of the brake rigging of the car, associated with each truck, are indicated by 23—23. These brake beams are disposed in the truck respectively in front of and to the rear of the bolster 18, that is, are located at the front and rear portions of the truck. Brake shoes 24—24 cooperate with the wheels 19—19 in a well-known manner, said shoes being carried by the brake beam heads 25—25, of well-known design, fixed to the brake beams 23—23. Each brake beam 23 includes the usual compression and tension members 26 and 27, the brake beam shown being of the well-known truss construction which has the compression and tension members thereof separated at the middle by a strut or fulcrum, to which the truck brake lever is attached for actuating the beam to apply and release the brakes by moving the brake shoes into and out of engagement with the brake wheels.

In carrying out my invention, I provide friction shoes A—A fixed to opposite ends of the brake beams 23—23 of the car truck and frictionally engaging the truck bolster to retard vertical movement thereof, thus snubbing the action of the truck springs.

Referring to the embodiment of the invention illustrated in Figures 1, 2, and 4, and the modification illustrated in Figure 3, it is pointed out that the construction and design involved is the same in Figure 3 as in Figures 1, 2, and 4, with the exception that a tension spring B is used for forcing the friction shoes A against the truck bolster.

Each friction shoe A is preferably in the form

of a casting including a vertically disposed end wall or plate member 28, a transverse bottom wall 29 extending outwardly from the lower end of the wall 28, and spaced webs or side flanges 30—30 connecting the end and bottom walls. At the outer side of the casting, a transverse web 31, parallel to the bottom wall, is provided between the side flanges 30—30 and above said bottom wall. The web 31 is connected at its inner end to the bottom wall 29 and the flanges 30—30 by a vertical wall section 32. A laterally outwardly projecting guide lug 33 is provided at the bottom of the shoe A adapted to slide in the guideway 14 of the truck side frame 10 at the corresponding side of the truck, the lug 33 being hollow and having top and bottom walls 34 and 35, which are continuations of the web 31 and the bottom wall 29, and a vertical end wall 36 connecting the top and bottom walls 34 and 35. The opening of the hollow lug is continuous with the opening between the web 31 and the bottom wall 29 of the shoe, a continuous socket 40 is thus provided adapted to receive the corresponding end of the member 28 of the brake beam 23.

The friction shoes A are four in number for each truck, said shoes being arranged in pairs at opposite ends of the brake beams 23—23, the members of each pair being disposed at opposite sides of the truck bolster 18 with the plate members 28—28 thereof adapted to engage the opposed vertical side faces of the bolster. The shoes A—A at opposite ends of each brake beam are mounted on the ends of the compression member 26 of said beam, the ends of the member 26 being seated in the sockets 40—40 of the shoes.

The brake beam heads 25—25 at opposite ends of each brake beam are provided with spaced, attaching flanges 37—37 for mounting the same on the brake beam, the flanges 37—37 of each brake beam head embracing the web 31 and the wall 29 of the corresponding friction shoe A therebetween. Any suitable means may be employed for securing the brake beam heads 25 and the friction shoes A to the brake beam 23. As shown in the present instance, these parts are secured by rivets 38—38 extending through the flanges 37—37 of the brake beam heads 25, the web 31 and the bottom wall 29 of the friction shoe A, and the corresponding end of the compression member 26 of said brake beam.

As will be evident, the shoes A—A at each side frame 10 of the truck embrace the truck bolster 18 at opposite sides and move in unison with the brake beam away from and toward the bolster as the brakes are respectively applied and released. The releasing action of the brakes thus brings the friction shoes A—A into tight frictional contact with the bolster to resist vertical movement thereof and snub the action of the truck springs.

Referring to the modification of the friction snubber as shown in Figure 3, the spring B connects the friction shoes A—A at opposite sides of the bolster, the shoes being provided with inwardly projecting eyes 39—39 to which the opposite ends of the spring are anchored, the spring having the tangs thereof formed into hooks 41 engaged in said eyes. The spring B is of the tension type and the force thereof is added to the force of releasing action of the brakes to bring the shoes into tight frictional contact with the bolster. Although the force exerted by the releasing action of the brakes is sufficient to press the shoes against the bolster to snub the action of the truck springs, the spring B is used when

it is found desirable to increase the snubbing action.

I have herein shown and described what I now consider the preferred manner of carrying out my invention, but the same is merely illustrative and I contemplate all changes and modifications that come within the scope of the claims appended hereto.

I claim:

1. In a railway car truck including side frames at opposite sides of the truck, wheels carried by said truck, a truck bolster vertically guided in said side frames, and truck springs supporting said bolster on the side frames, the combination with brake beams at opposite sides of said bolster having brake shoes cooperating with the truck wheels, said beams being movable away from and toward the bolster as the brakes are applied and released; of friction shoes at opposite sides of said bolster fixed to the brake beams and movable therewith toward the bolster to engage the same when the brakes are released, said shoes having friction faces engageable with opposite sides of the bolster to frictionally oppose vertical movement of the latter and snub the action of the truck springs.

2. In a railway car truck including a side frame, a truck bolster guided for vertical movement in said side frame, and truck springs supporting said bolster on the side frame, the combination with a brake beam laterally movable toward and away from the side of said bolster when the brakes are respectively released and applied; of a friction shoe fixed to said brake beam, said shoe having a friction surface, said shoe being moved into engagement with the side of the bolster by movement of said beam toward the bolster and thereby retard vertical movement of the bolster and snub the action of the truck springs.

3. In a railway car truck including a side frame, a truck bolster guided for vertical movement in said side frame, and truck springs supporting said bolster on the side frame, the combination with a brake beam laterally movable toward and away from the side of the bolster, when the brakes are respectively released and applied; of a friction shoe having a friction surface engageable with said bolster, said shoe being fixed to the brake beam and movable therewith toward the bolster to engage the shoe with the bolster and retard vertical movement of the latter to snub the action of the truck springs; and cooperating guide means on said shoe and side frame for guiding the shoe and brake beam.

4. In a railway car truck including a side frame, a truck bolster guided for vertical movement in said side frame, and truck springs supporting said bolster on the side frame, the combination with a brake beam laterally movable toward and away from the side of the bolster, when the brakes are respectively released and applied; of a friction shoe having a friction surface engageable with said bolster, said shoe being fixed to the brake beam and movable therewith toward the bolster to engage the shoe with the bolster and retard vertical movement of the latter to snub the action of the truck springs; a laterally extending guideway on the side frame; and a guide lug on said shoe slidably guided in said guideway.

5. In a railway car truck including a side frame, a truck bolster guided for vertical movement in said side frame, and truck springs supporting said bolster on the side frame, the com-

bination with a brake beam laterally movable toward and away from the side of the bolster, when the brakes are respectively released and applied; of a friction shoe having a friction surface engageable with said bolster, said shoe being fixed to the brake beam and movable therewith toward the bolster to engage the shoe with the bolster and retard vertical movement of the latter to snub the action of the truck springs; a laterally extending guideway on said side frame, said guideway being inclined upwardly and outwardly; and a lug on said shoe slidably guided in said guideway.

6. In a railway car truck including side frames at opposite sides of the truck, wheels carried by said truck, a truck bolster vertically guided in said side frames, and truck springs supporting said bolster on the side frames, the combination with brake beams at opposite sides of said bolster having brake shoes cooperating with the truck wheels, said beams being movable away from and toward the bolster as the brakes are applied and released; of friction shoes at opposite sides of said bolster fixed to the brake beam and movable therewith toward the bolster to engage the same when the brakes are released, said shoes having friction faces engageable with opposite sides of the bolster to frictionally oppose vertical movement of the latter and snub the action of the truck springs; and a tension spring extending between and fixed at opposite ends to said shoes which are at opposite sides of the bolster for forcing said shoes against the bolster.

7. In a railway car truck including a side

frame, a truck bolster guided for vertical movement in said side frame, and truck springs supporting said bolster on the side frame, the combination with a pair of brake beams respectively at opposite sides of the bolster, said beams being laterally movable away from and toward said bolster when the brakes are respectively applied and released; of a friction shoe fixed to each brake beam, said shoes having friction surfaces, said shoes being movable into engagement with opposite sides of the bolster by movement of said brake beams toward the bolster to retard vertical movement of the latter and snub the action of the truck springs; and spring means for forcing said shoes against the bolster.

8. In a railway car truck including a side frame, a truck bolster guided for vertical movement in said side frame, and truck springs supporting said bolster on the side frame, the combination with a pair of brake beams respectively at opposite sides of the bolster, said beams being laterally movable away from and toward said bolster when the brakes are respectively applied and released; of a friction shoe fixed to each brake beam, said shoes having friction surfaces, said shoes being movable into engagement with opposite sides of the bolster by movement of said brake beams toward the bolster to retard vertical movement of the latter and snub the action of the truck springs; and a tension spring connecting said shoes and forcing the same against the bolster.

GEORGE E. DATH.
